HOSE SUPPORTER GRIPPING DEVICE

Jennie M. Bodensiek, New York, N. Y.

Application February 12, 1935, Serial No. 6,178

5 Claims. (Cl. 24—245)

This invention relates to corset hose-supporter gripping devices and has for one of its objects the provision of a button-type gripping device which is substantially flat and provided with means for adjustably clamping same to a hose supporter or garter elastic without sewing the said garter to the clasp so that the gripping device may be readily removed from the garter when the corset or other garment is to be laundered.

Another object of the invention is to provide such a gripping device in which the frame, hose-gripping loop or yoke and garter gripping buckle are made of one piece of material, thus eliminating the use of the connecting sleeves which are now commonly used and which often come apart when a heavy strain is put on the device.

A further object of the invention is to provide a device of this character in which the hose-clamping disk or button and its base are made out of a single piece of any suitable material such as metal, bakelite or composition, to avoid riveting of the said parts and the resultant joint which is detrimental to the hose.

Still another object of the invention is the provision of a rubber ring or collar which is rotatable about the shank of the clamping button so as to provide a give or slight rotation of the stocking when the wearer moves her leg and thus preventing tearing or runs when a sudden pull or jerk is placed upon the button by such movement.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one

of which, for the purpose of illustration, is shown in the accompanying drawing, in which—

Figure 1 is a perspective view of my improved gripping device.

Figure 2 is an enlarged front view in elevation thereof, shown as applied to a stocking.

Figure 3 is a section taken on line 3—3, Figure 2.

Figure 4 is a sectional view taken on line 4—4, Figure 2.

Figure 5 is a perspective view partly broken away at an enlarged scale of the combined base and clamping button, and

Figure 6 is a perspective view of the combined frame, clamping loop and garter clamp.

Referring now to the drawing in detail 10 indicates an elastic strip or garter depending from a corset or other garment 11. Adjustably suspended from the said strip 10 is a hose gripping device 12 which comprises a frame 13 having at 20 the top thereof a garter clasp or toothed grip 14 below which and spaced therefrom there is provided a bar 15 about which the garter 10 is entwined through slots 16 and 17. The said frame is further provided at the bottom thereof with 25 a loop 18 which cooperates with a button or disk 19 for clamping the hose 20 therebetween.

The said button or disk 19 forms a part of and is integral with a base 21 provided with slots 22 through which passes a ribbon 23 the ends of 30 which are fastened or clampingly held in a bent-up ear 24 at the rear of the frame 13 directly below the slot 17. The combined button 19 and base 21 is provided with a connecting shank 25 upon which there is loosely mounted a rubber ring 35 or washer 26.

The operation of the device is as follows:

To insert the stocking into the gripping device, the button 19 is slid upwardly from the narrow portion 18a of the loop 18 into the wide portion 18b and disengaged therefrom. The upper portion of the stocking 20 is then placed over the button 19 and clamped thereabout and the rubber ring 26 by the engagement of the loop 18 therewith. To adjust the gripping device on the elastic strip or garter 10, the said garter is disengaged from the toothed bar 14, and slid into proper position and then reengaged with the said toothed bar.

It will be understood that due to the comparatively loose mounting of the rubber ring 26 on the shank 25, the stocking 20 will be permitted to give or move with the movement of the wearer's leg, thus preventing tearing or runs, when the 55

stocking about the button is subjected to a sudden pull or jerk.

It will further be seen that due to the absence of joints between the button 19 and base 21, 5 the stocking cannot be caught and torn by such joints. Furthermore, it will be seen that the entire device is very thin and will not cause any bulges in the dress of the wearer due to the fact that the elastic does not have to be folded over 10 and sewn to the supporting buckle in the manner now done in the button type of clamping device in common use.

A still further advantage of my improved hose clamping device is that the frame is of a single 15 piece and not of a plurality of buckles or clasps joined by jackets or sleeves which are liable to come apart.

From the foregoing, it will be seen that I have 20 provided a simple and efficient combined clamp and buckle that will positively grip the hose without causing any runs therein, and one that can be readily adjusted on the garter strip without the use of a doubled or folded over elastic for the hose supporter or garter.

25 It will further be seen that the entire device may be readily slipped off the garter strip when the corset is laundered without ripping any stitches.

Having described my invention, what I claim 30 as new and desire to secure by Letters Patent is:

1. A hose supporter gripping device, comprising

ing a hose gripping loop-bearing frame, a base plate supported on the said frame, a hose gripping button integral with the said base plate, and an elastic ring rotatably supported on the said button. 5

2. A hose supporter gripping device, comprising a hose gripping loop-bearing frame, a base plate supported on the said frame, a shank extending from the base and integral therewith, a disk integral with the shank, and an elastic ring rotatably mounted on the shank. 10

3. A hose supporter gripping device, comprising a frame, garter gripping means integral with the frame at one end thereof, a hose gripping loop integral with the frame at the opposite end thereof, a base plate suspended from the frame, a shanked button integral with the base plate, and an elastic ring rotatably mounted on the button shank. 15

4. A hose supporter gripping device, comprising an integral hose gripping loop-bearing and garter gripping frame, a base plate suspended from the said frame, a shanked button integral with the said base plate, and an elastic ring rotatably mounted on the button shank. 20

5. A hose supporter gripping device, comprising a hose gripping loop, a base plate, a button on the said base plate, and a yieldable ring rotatably supported on the said button. 25
